UNITED STATES PATENT OFFICE.

NAPOLEON BOUDREAU, OF GARDEN, MICHIGAN.

CAR-COUPING.

SPECIFICATION forming part of Letters Patent No. 415,701, dated November 26, 1889.

Application filed June 24, 1889. Serial No. 315,310. (No model.)

To all whom it may concern:

Be it known that I, NAPOLEON BOUDREAU, a citizen of the United States, residing at Garden, in the county of Delta and State of Michigan, have invented certain new and useful Improvements in Car-Couplers; and I do declare the following to be a full, clear, and exact description of the invention, such as will enable others skilled in the art to which it appertains to make and use the same, reference being had to the accompanying drawings, and to the letters of reference marked thereon, which form part of this specification.

My invention relates to car-couplers, and it looks to an improvement of that class of link-and-pin couplers in which a rolling body is employed to support the pin when raised up out of engagement with the link, the arrangement being such that the rolling body is knocked out from under the pin by the end of a link entering the draw-head, thereby allowing the pin to drop and engage with the link. In these couplers as heretofore constructed the rolling pin-support cannot move into position to support the pin until the link has been withdrawn from the draw-head, being forced into the back of the draw-head and retained there by the link. It is therefore impossible to separate the cars unless the pin is not only raised but removed from the draw-head.

In making up trains and the like it is important to economize the time of the men employed and to use no more men than are necessary, and in the operation of coupling and uncoupling cars it is frequently of advantage to be able to raise the pin, so as to release the link, and yet leave it in condition to couple automatically when the cars come together again. My invention is designed to meet this requirement, in that it enables the pin to be raised and held up by the rolling support before the link is withdrawn and remain supported ready to couple automatically when the link again enters the draw-head.

In the drawings, Figure 1 is a perspective view of a portion of the end of a car provided with my improvements with the pin down. Fig. 2 is an end view of the draw-head with the pin raised. Figs. 3 and 4 are vertical sections of the draw-head with the pin raised,

and Fig. 5 a horizontal section of the draw-head with the pin down.

The mouth of the draw-head A opens into a chamber a, which has parallel side walls, 55 and to which access can be had through an opening in the top of the draw-bar closed by a suitable lid a'. On each side of the chamber is an inclined ledge B, which may be integral with the draw-head or inserted into it. 60 The incline commences at or near the mouth of the draw-head and runs back at a sharp angle with the floor of the chamber a to a point beyond the center of the pin-hole a². Here its direction changes to a lesser angle with 65 the floor of the chamber, and it runs back to the rear wall of the chamber, preferably on a gentle upward curve during the last third of its length. The junction of the two portions of the incline forms an obtuse angle b, which 70 lies to the rear of the axis of the pin-hole a². The rear portion of the ledges B is preferably thickened laterally, being curved, as shown in Fig. 5, to match the end of the link C, the width of the link being such as to fit easily 75 between the ledges, whereby, when it is pushed back into the draw-head, it is held in line with the center of the same. The outer ends of the ledges B are rounded off at b' to facilitate the entrance of the link. 80

The opening in the top of the draw-head is of such a size as to readily admit to the chamber a a roller D, which is received upon the edges B and is preferably provided with a groove d around its middle. The diameter of 85 the roller is such that when it lies against the front wall of the chamber a its axis intersects the axis of the pin-hole a². In this position it rests upon the angle b of the incline, and inasmuch as the point of contact is 90 to the rear of the axis of the roller the tendency of the latter is to resist any force acting to roll it back into the draw-head, since it must rise slightly to get over the angle b. The mouth of the draw-head is so proportioned that only the lower half of the roller is exposed, so that the link is compelled to pass under the roller. The height of the ledges at the angle b is less than the thickness of the end of the link, so that the link on 95 entering will somewhat lift the roller and carry it back into the draw-head. 100

It will be seen that there is room enough in the chamber *a* for the roller *D* in the rear of the pin *E*, the roller resting on the incline against the pin, as shown in Fig. 5. When 5 the pin is lifted, the roller will gravitate to the position in which it is shown in Fig. 4, the body of the link being thinner than its ends to allow the roller to settle down in front of the angle *b*. In this position the pin *E* is 10 supported by the roller with its end in the groove *d*. The link can now be withdrawn without disturbing the pin, since the roller merely rises slightly as the end of the link passes under it and then settles down into 15 place again, as shown in Figs. 2 and 3. When the link enters again, it knocks the roller out from under the pin and allows it to drop into place. Even if the link enters slowly and 20 gently, the roller is carried back by rolling contact with the link, so that the pin is sure to be dropped, however the link may enter. The groove *d* in the roller guides the pin into the lower pin-hole *a*².

In order that the train-man may lift the pin 25 without going between the cars, a rock-shaft *F* is supported in bearings across the end of the car, having at each end a depending handle *f*. An arm *f'* projects from the rock-shaft over the draw-head, the end of the arm being 30 connected by a link *G* with the head of the pin *E*.

When a car is to be uncoupled, the train-man has merely to rock the shaft *F* in its bearings, thereby raising the pin, which is in 35 stantly caught and held by the roller *D*, leaving the link free to be pulled out when the cars separate and the pin ready to automatically couple with a link when it enters the draw-head.

40 Having thus described my invention, what I

claim, and desire to secure by Letters Patent, is—

1. The combination, with a draw-head provided with fixed inclined ledges, of a roller supported on said ledges and adapted to roll 45 under and support the pin when raised before the link is withdrawn, substantially as described.

2. The combination, with a draw-head containing inclined ledges composed of two inclines meeting at an obtuse angle, of a roller supported on said ledges and adapted when supporting the pin to rest with its axis in front of the obtuse angle, substantially as described. 50

55 3. The combination, with a draw-head containing the chamber *a*, of the inclined ledges *B* within the chamber, having laterally-curved inner ends, and the roller *D*, supported upon the ledges, substantially as described.

4. The combination, with a draw-head containing the chamber *a*, of the inclined ledges *B*, and the roller *D*, supported on said ledges above the floor of the chamber when the link is withdrawn, substantially as described. 60

5. The combination, with the draw-head containing the chamber *a* and provided with an opening in its top giving access to said chamber, of the inclined ledges *B* on each side of said chamber, and the roller *D*, having the groove *d*, adapted to be inserted 70 through the opening and be supported by its ends upon the ledges *B*, substantially as described.

In testimony whereof I affix my signature in 75 presence of two witnesses.

NAPOLEON BOUDREAU.
